UNITED STATES PATENT OFFICE.

WM. B. BEMENT, OF PHILADELPHIA, PENNSYLVANIA.

HANGER FOR SHAFTING.

Specification of Letters Patent No. 19,340, dated February 16, 1858.

To all whom it may concern:

Be it known that I, WILLIAM B. BEMENT, of the city of Philadelphia and State of Pennsylvania, have invented a new and useful Improvement in Hangers for Shafting of Mills, Factories, &c.; and I do hereby declare that the following is a full, clear, and exact description of the construction and operation of the same, reference being had 5 to the accompanying drawings, making a part of this specification, in which—

Figure 1 is a geometrical side elevation of the improved hanger; Fig. 2, a like front elevation of the same; Fig. 3, a vertical section of the same; Fig. 4, a horizontal section (through F, F, of Fig. 1) showing the relative positions of the adjusting screws, stem, and bushing of the box holder for the same; Fig. 5 is a side elevation of the 10 pillow block with the same improvement applied which is shown in the Figs. 1, 2, and 3; Fig. 6, a front elevation of the same; and Figs. 7, 8, and 9 are representations of the same improvement adapted to trunnions 15 for the same purpose; Fig. 10 denotes a side elevation of the hanger with the annular part B, of the box holder, and the box C, and shaft below the hanger, or showing the hanger elongated; Fig. 11 is a transverse 20 and vertical section of Fig. 10, showing the capabilities and relative arrangement of parts for universal adjustment of the line of shaft, box, and of box carriers position all combined in the same hanger; Fig. 12 25 is a plan of Figs. 10 and 11 with front end of hanger broken off to show parts below, and how the shaft may be run in any direction or line in the horizon or complete circle when below the hanger, and 30 the same above with the exception of the slight thickness of the body of the hanger; also showing how the shaft may be run on any angle with the hanger and still have all the universal coöperative adjustments, 35 at the same time as to line of shaft, and position of box whether above or below the support as hereafter seen.

Like letters indicate the same parts, when on the different figures.

50 The nature of my invention consists of my within described main part of the hanger so constructed as within described as to so receive the parts connected to and to coöperate with it, that the shaft and box 55 may have both an universal line adjustment, and a universal position adjustment, and

also to run above or below the support part of the hanger, in the manner hereinafter described. And in the relative arrangement and operation of the several parts, in combination with each other, and the hanger, as to allow the shaft an universal line position as to horizon; to be operated above or below the hanger, (or that portion which supports it) for the desired elevation, and 60 at the same time allow an universal radial self-adjustment of the box, to coöperate with the shaft, and so that the box and shaft may both have an universal position adjustment so as to be moved to find any point 65 or location within the scope limits of the hanger, and so secured, to constitute it a complete machine for the purpose designed, all as will be hereafter seen.

B, the annular part of the box support 75 or holder; C, the box through which the shafting passes; E, the bushing surrounding the stem of the holder; F, the set screws for adjusting the box holder horizontally; G and H, screw nuts adapted to a thread 80 which is cut upon the stem (K) of the box holder.

I, represents the tubular part of the hanger through which the stem of the box holder or supporter is inserted, and around 85 and through the upper part of which the adjusting screws (F) are radially inserted; and O, O, are pointed screws for supporting the box when applied by means of trunnions. The dotted lines A', B', and C' D' 90 are vertical and horizontal indications of the center of the shafting.

The stem of the hanger may be made in the usual form, and as usually adapted for being secured by bolts and nuts. The part 95 to which the box is usually applied I make of an elliptical form and tubular, and so that it shall be in a vertical position when the hanger, pillow block or bracket is applied; and through this, the stem (K) of 100 the box supporter, having a thread cut upon it, is adapted to slide freely up and down, and also so as to be capable of being firmly adjusted therein at any height (within proper limits by means of the two screw 105 nuts (G and H) which are adapted to the thread thereon and so as to bear respectively against each end of the tube, as shown in the drawings. The upper side of the annular part of the box holder (B) has a socket 110 adapted for receiving and holding the box by means of a spherical form given there-

to—(an arrangement well known and therefore not needing a description). This annular part (B), is also constructed so as to be a fixed part of the screw stem (K), and consequently the box is carried up or down with the single stem as the latter is raised or lowered by operating the nuts G and H.

The box (C) is constructed in the usual manner, being fitted with oil cups and 10 conducting holes on the upper side and adapted for the reception of the shaft.

For the purpose of effecting the horizontal adjustment of the box holder in directions at right angles with the shafting, I make 15 the upper part of the tube (I) larger than the lower part, so as to allow of sufficient room being made within the same for the reception of the bushing (E) which surrounds the stem (K) at this point, and also 20 so as to allow a horizontal movement of the said stem and bushing in directions at right angles with the shafting, when the set screws (F, F, F,) are operated for the purpose of adjusting the same, as shown in Fig.

25 4. These screws (F) are placed radially around and through the sides of the tube (I) so as to bear with their inner ends against the bushing (E) as shown in the same figure. Now the tube (I) being also 30 elliptical in its bore, or on the inner side, and having its longer diameters at right angles with the shafting, and its shorter diameters about equal with the diameters of the stem (K) and the bushing (E) respectively, it will be manifest that the stem (K), 35 fitting closely through the bushing (E), is capable of being readily moved therewith in the horizontal direction mentioned, by simply operating the set screws (F, F, F)

40 accordingly, and that the said stem (K) supporting the box or bearing (C) of the shaft, and being capable of a vertical motion in the tube by means of the screw thread thereon in combination with the screw nuts (G 45 and H) as before described the said box is therefore capable of being moved (within proper limits) in directions either vertical, horizontal or in any resultant of the two combined—which in connection with the in- 50 dependent ball and socket motion which the box has within the annular part (B) of the support, enables the workman at any time, readily to bring the center of the shaft to coincide perfectly with any point (within 55 necessary limits), without requiring any re-adjustment of the hanger, and without removing the said shafting therefrom—as has heretofore been necessary whenever the said hangers &c. have gotten “out of line,” a re- 60 sult of very frequent occurrence, and arising from the sinking of parts of the building, shrinking of the beams to which the attachments are made, and other causes.

It requires a close examination of the be- 65 fore described adjustability and parts con-

stituting it to comprehend the full extent and effect of this improvement as follows, by the vertical adjustment of the general position of the box by means of the stem K a vertical adjustment only; would be had, 70 while by the arrangement described a vertical, horizontal, transverse and in fact an universal adjustment is had, of the shafts position in every direction, whereby any and every point or position within the scope 75 limits of the hanger can be readily found and permanently secured, and combined with the universal self adjustment of box and shaft to each other, this result is due to the novel and relative arrangement of the different parts of the hanger in combination with each other, and the main part of the hanger, it is of vital importance and the hanger would not be a complete machine without it.

The same improvement may also be applied to boxes upon trunnions constructed as usual, by means of set screws O, O, which are pointed so as to fit in conical depressions made in the ends of the trunnions as shown 80 in Fig. 7, the support for the trunnion screws, being formed so as to receive the box and be adjustable in the vertical and horizontal directions by means of the screw-stem and nuts (G and H), and the set 85 screws (F) as before described and set forth.

It will be perceived that my invention is applicable to all kinds of supports for shafts of mills, whether the said supports are suspended from above, secured against a wall, 100 or resting upon a base; and that the box for the shaft can be supported equally well for the purpose, whether the screw stem (K) be above or below the box. This arrangement allows of placing and running the shaft above the support of the hanger where the room is low and the pulleys small in diameter which constitutes the hanger a short one; and allows the shaft to be placed and run far below the support of the hanger 105 which constitutes the hanger a long one, thereby allowing very large pulleys to be used thereon as seen at Figs. 10, 11, and 12, it also will allow the line of shafting to be placed, and run in any line within the whole 110 horizon, below the hangers; and nearly so when the shaft is above the support as seen by red lines A², Fig. 12, and still by the construction and peculiar combination of parts, allow of the shafts and box universal self 115 adjustment to each other, or to coöperate freely together and at the same time allow of an universal adjustment as to general position of shaft. This is also a very important improvement and wholly due to the peculiar construction and arrangement of the parts constituting my invention.

The advantages of my invention are that a line of shafting, or a single shaft, can in case of the settling of the building, shrink- 120 125 130

ing of the beams, or wearing of the boxes or bearings, be easily and firmly readjusted or "relined," at the same time, without readjusting the hangers &c. and without removing the shafting therefrom as before stated.

Having thus described the construction and operation of my invention, and pointed out peculiar facts showing its great utility—I proceed to state that I do not claim supporting a box or bearing for a shaft upon trunnions cast on the box; nor suspending the same upon the pointed ends of screws—nor do I claim the more common arrangement for holding the box so as to allow a "universal motion" of the same, by means of the "ball and socket;" nor do I claim adjusting the same vertically, by means of a screw and two nuts, the former sliding up and down in a cylindrical tube.

What I claim as my invention and desire to secure by Letters Patent is,

1. The main part or body of the hanger A, or its equivalent, when so constructed as to receive the parts which are so connected to, and to coöperate with it, that both the shaft and box shall have an universal line adjustment and an universal position adjustment, and at the same time allow the

shaft to be placed and run above or below the support part of the hanger, in any and every horizontal and angular line, substantially in the manner and for the purposes fully described and set forth.

2. I claim the construction of the single stem (K) carrying the box (C) and so arranging it relatively with and connecting it to the hanger or support by bushing (E) that the box and shaft shall have a coöoperative self and universal line adjustment with each other, and the shaft have an universal position adjustment so as to be moved readily to find any and every point or location within the required limits and be secured therein, and so that the line of the shaft may be placed and run above the support or below the hanger to constitute it a long or short one, and also receive any and every line and self adjustment positions within a complete horizon or circle, essentially in the manner and for the purposes fully set forth and described.

WM. B. BEMENT.
